Primary Examiner — Katherine Glennon*(74) Attorney, Agent, or Firm* — Westbridge IP LLC(57) **CLAIM**

The ornamental design for a wrist watch with earphones, as shown and described.

DESCRIPTION

FIG. 1 is a front perspective view of a wrist watch with earphones showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 in FIG. 2;

FIG. 10 is an enlarged view of portion 10 in FIG. 5; and,

FIG. 11 is another front perspective view thereof, in which the earphones are separated from the wrist watch for ease of illustration.

The evenly broken lines in the drawings illustrate portions of the wrist watch with earphones that form no part of the claim.
